Primary Examiner — T Chase Nelson*Assistant Examiner* — Kelly L Gross(74) *Attorney, Agent, or Firm* — Schwegman Lundberg & Woessner, P.A.(57) **CLAIM**

We claim the ornamental design for an oxygen imaging instrument, as shown and described.

DESCRIPTION

FIG. 1 is a top, isometric view of an embodiment of an oxygen imaging instrument;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines showing in the figures are included for the purpose of illustrating portions of the oxygen imaging instrument system which form no part of the claimed design. The dash-dot lines showing in the figures are included for defining the bounds of the claimed design that form no part thereof. The portions of FIGS. 1, 2, and 6 shaded with oblique lines are included for the purpose of illustrating portions of the oxygen imaging instrument that are a screen.
